ASH TRAY

Harry M. Anholt, 299 Park Ave., New York, N.Y.

Filed Nov. 6, 1962, Ser. No. 72,408

Term of patent 14 years

(Cl. D85—2)

FIG. 1

FIG. 2

FIG. 3

FIG. 4

FIG. 1 is a view in perspective of an ash tray showing my new design.

FIG. 2 is a top plan view;

FIG. 3 is a bottom plan view; and

FIG. 4 is a cross-sectional view taken on the line 4—4 of FIG. 2.

I claim:

The ornamental design for an ash tray, substantially as shown.
